UNITED STATES PATENT OFFICE

JOHN N. NELSON, OF CRANSTON, RHODE ISLAND, ASSIGNOR TO UNIVERSAL OPTICAL CORPORATION, A CORPORATION OF RHODE ISLAND

DESIGN FOR AN OPHTHALMIC MOUNTING

Application filed September 17, 1930. Serial No. 36,998. Term of patent 14 years.

To all whom it may concern:

Be it known that I, JOHN N. NELSON, a citizen of the United States of America, residing in Cranston, county of Providence, State of Rhode Island, have invented a new, original, and ornamental Design for an Ophthalmic Mounting, of which the following is a specification, reference being had to the accompanying drawing, forming a part thereof.

Fig. 1 is a face view and Fig. 2 is a top edge view of an ophthalmic mounting, showing my new design.

I claim:

The ornamental design for an ophthalmic mounting, substantially as shown.

JOHN N. NELSON.
